(57) **CLAIM**

The ornamental design for a kiosk as shown and described.

DESCRIPTION

FIG. 1 is a front perspective view of a kiosk in accordance with the new design;

FIG. 2 is a front view thereof;

FIG. 3 is a rear view thereof;

FIG. 4 is a left side view thereof;

FIG. 5 is a right side view thereof;

FIG. 6 is a partial enlarged front perspective view of a kiosk, according to a second embodiment of the design, the only difference from the design of the kiosk of FIG. 1 being the front panel features;

FIG. 7 is a partial enlarged front perspective view of a kiosk, according to a third embodiment of the design, the only difference from the design of the kiosk of FIG. 1 being the front panel features; and,

FIG. 8 is a partial enlarged front perspective view of a kiosk, according to a fourth embodiment of the design, the only difference from the design of the kiosk of FIG. 1 being the front panel features.

The broken lines in the drawings depict portions of the kiosk that form no part of the claim.

The dot-dash broken lines form no part of the claim, and are included to define the boundary of the enlarged views depicted in FIGS. 6-8.

1 Claim, 8 Drawing Sheets
